Harry T. Keel
INVENTOR

BY Alfred J. Boratton

ATTORNEY.

UNITED STATES PATENT OFFICE.

HARRY T. KEEL, OF CHESTER, PENNSYLVANIA.

WINDING REEL.

Application filed November 4, 1922. Serial No. 599,137.

To all whom it may concern:

Be it known that I, HARRY T. KEEL, a citizen of the United States, residing at Chester, in the county of Delaware and State 5 of Pennsylvania, have invented a new and useful Winding Reel, of which the following is a specification.

This invention relates to winding reels and it has more particular reference to reels 10 for winding up clothes lines and the like promptly and neatly, the primary object had in view being to provide a winding reel of the type referred to which will evenly coil up a line quickly thereon without any 15 bulges or unsightly protrusions.

Another object of my invention is to provide a winding reel that is very effective in use, simple in construction, and cheap to manufacture.

20 A further object of this invention is the provision of a winding reel that is readily adjustable for the coiling or winding up thereon of lines of different length or diametric size.

25 With the foregoing and other objects in view as will be apparent from the following description, my invention consists in the novel features of construction, combinations and arrangements of parts hereinafter fully 30 described and more specifically defined by the appended claims.

In the further disclosure of the invention reference is to be had to the accompanying sheet of explanatory drawings constituting 35 a part of this specification, and in which like characters of reference designate the same or corresponding parts in all the views.

Figure 1 is a broken plan view of my novel winding reel with a portion of a line 40 wound thereon, said line being indicated by dot-and-dash lines.

Figure 2 is a side view of the preceding figure.

Figure 3 is a detail plan of a keeper hereinafter more fully described; and

45 Figure 4 is a side view looking to the left hand of Figure 3.

Referring more particularly to the drawings the numerals 5, 6 designate a pair of 50 rectangular cross section parallel bars conveniently made of wood or other suitable light and durable material, and said bars 5, 6 have their inner end parts oppositely cut away or tapered at 7, to aid in winding a 55 long line as hereafter explained. 8, 9 are

cross bars, preferably wooden rounds, the former of which is secured at one end by a sprig or nail 10 in a hole 11 of like diameter provided for the purpose in the bar 6 while its free end 12 is a sliding fit through a 60 hole 13 in the bar 5. Similarly the cross bar 9 is retained by a sprig or nail 14 in a hole 15 in the bar 5, while its free end 16 is a sliding fit through a hole 17 in the bar 6. An examination of the drawings will 65 establish the fact that the aforesaid free ends 12, 16 constitute hand-holds by means of which the reel can be operated or rotated for winding up a line.

In order to provide a simple means where- 70 by the aforesaid parallel bars 5, 6 may be adjusted in space relation, I provide each of the cross bars 8, 9 with a series of equally spaced grooves or kerfs 18, with which co- 75 operate hooks 19 appropriately pivoted on the outer faces of the aforesaid bars 5, 6 by means of wood screws or the like 20. Thus it will be clearly apparent to those acquainted with the art that by unlatching the hooks 19 the parallel bars 5, 6 may be easily varied 80 in parallel spaced relation, and relocked securely at the requisite adjustment by relatching the hooks 19. This feature I deem of value in that it renders my novel winding reel easily adaptable for lines of dif- 85 ferent length and diametric size.

In some instances the hooks 19 may be dispensed with and the parallel bars 5, 6 maintained in rigid spaced relation by 90 springs or nails 21, as will be readily understood by those conversant with the art.

A metal keeper 22 of appropriate dimensions is secured centrally of the inner face of one of the aforesaid parallel bars—5 for example—by means of nails or screws 23 95 passed through holes 24 in the flanges 25 thereof. Now it will be perfectly obvious that if one end of a line 26 is passed through this keeper 22 and knotted at 27 it can be easily wound upon the cross bars 8, 9 without creating any bulges in that the inner or attached end of said line is securely retained out of the winding path when the device is in use.

The aforesaid winding reel will be found 105 especially adapted for clothes lines, and in use the operator will, when stringing a line, firstly attach the free end of the line 26 to a post or other stationary fixture where- 110 upon said line can be unwound by the user

grasping the free ends or hand holds 12, 16 in his or her hands and rotating the device with a crank like movement in a counter-clockwise direction. After stringing the line 26 properly it will be easily seen that the device is not disconnected therefrom due to the connection of said line into the keeper 22. In taking down the line the operation of the reel is reversed and it will be understood that a sufficient tension can be exerted thereon to snugly rewind the line on the reel, while the cut away or tapered ends 7 will aid in guiding the line into position as each convolution is completed.

15 While there has been shown and described a preferred form of the invention, it will be obvious the same is susceptible of minor detail changes as well as other usages, and the right is accordingly hereby reserved to 20 make such variations as fairly lie within the scope of the appended claims.

Having described my invention what I claim as new and desire to secure by Letters Patent is:

25 1. A winding reel comprising a frame consisting of a pair of parallel bars and a pair of cross bars, said cross bars each having an end projecting beyond one of said parallel bars, said projecting ends having a 30 plurality of spaced notches, and hooks pivoted on the parallel bars and adapted to engage said notches whereby the parallel

bars may be secured in adjustable spaced relation to the cross bars.

2. A winding reel comprising a frame 35 consisting of a pair of parallel bars and a pair of cross bars, said cross bars each having an end projecting beyond one of said parallel bars, and means secured to said parallel bars and cooperating with means 40 on the cross bars whereby the parallel bars may be releasably held in adjusted spaced relation.

3. A winding reel embodying a frame including a pair of rectangular cross-section 45 parallel bars having their inner ends opposingly inclined outwards, a pair of round section cross bars intersecting and maintaining the aforesaid parallel bars in spaced relation, one of said cross bars projecting 50 at one side and the other at the opposed side of said frame to provide hand holds, equally spaced notches in the hand holds and cooperative pivoted hooks on the outer faces of the parallel bars for varying the distance between said parallel bars while retaining the same and the cross bars in secure relation, and a keeper mounted centrally on the inner face of one parallel bar for receiving the knotted end of a line. 55

Signed at Chester, county of Delaware and State of Pennsylvania, this 25th day of October, 1922.

HARRY T. KEEL.
